CLAIM

The ornamental design for a dispensing closure, as shown and described.

DESCRIPTION

FIG. 1 is a perspective view of a dispensing closure in accordance with the invention shown with a top lid in the closed position;

FIG. 2 is a front view of the dispensing closure from FIG. 1;
FIG. 3 is a back view of the dispensing closure from FIG. 1;
FIG. 4 is a right side view of the dispensing closure from FIG. 1;

FIG. 5 is a left side view of the dispensing closure from FIG. 1;

FIG. 6 is a top view of the dispensing closure from FIG. 1; and
FIG. 7 is a bottom view of the dispensing closure from FIG. 1.

FIG. 8 is a perspective view of the dispensing closure of FIG. 1 shown with the top lid in the opened position;

FIG. 9 is a front view of the dispensing closure from FIG. 8;
FIG. 10 is a back view of the dispensing closure from FIG. 8;
FIG. 11 is a right side view of the dispensing closure from FIG. 8;

FIG. 12 is a left side view of the dispensing closure from FIG. 8;

FIG. 13 is a top view of the dispensing closure from FIG. 8; and

FIG. 14 is a bottom view of the dispensing closure from FIG. 8; and,

FIG. 15 is a cross section view of the dispensing closure from FIG. 8.
